D. R. YARNALL,
BLOW OFF VALVE,
FILED SEPT. 18, 1919.

4 Inventor.
David Robert Yarnall.

by *W. Steel Johnson*
Attorney.

UNITED STATES PATENT OFFICE.

DAVID ROBERT YARNALL, OF PHILADELPHIA, PENNSYLVANIA, ASSIGNOR TO YARNALL-WARING COMPANY, OF PHILADELPHIA, PENNSYLVANIA, A CORPORATION OF PENNSYLVANIA.

BLOW-OFF VALVE.

Application filed September 18, 1919, Serial No. 324,618.

To all whom it may concern:

Be it known that I, DAVID ROBERT YARNALL, a citizen of the United States, residing at 316 Preston Street, Philadelphia, in 5 the county of Philadelphia and State of Pennsylvania, have invented a certain new and useful Blow-Off Valve, of which the following is a specification.

My invention relates to blow-off valves, 10 such as are used in steam boiler systems.

The purpose of my invention is to provide a quick-acting reliable blow-off valve which shall at the same time be of short face-to-face length in the direction of steam passage.

A further purpose is to supplement the holding power of a valve face held by pressure against a seat by a spring-pressed movable seat on the opposite side. 20 A further purpose is to provide a supplemental valve having two effective seats and capable of quick operation in tandem with a second blow-off valve having sure holding qualities.

25 Further purpose will appear in the specification and in the claims.

I have preferred to illustrate my invention by but one form each of swing-gate valve and slide gate valve among the forms 30 in which my invention might appear, selecting them as practical, efficient, simple and inexpensive and at the same time well illustrating the principles of my invention.

Figure 1 is a longitudinal section through 35 the center of the valve.

Figure 2 is a side elevation of the disk and of the arm by which it is swung.

Figure 3 is a broken longitudinal section showing a slight modification.

40 Figures 4 and 5 are a transverse section upon line 4—4 of Figure 5 and a side elevation, respectively, of a second form of the invention.

In the drawings similar numerals indicate 45 like parts.

Many power plants place their blow-off valves in pairs, arranged in tandem. This is required by law in some States. In such a case, it is necessary that one of the blow-off 50 valves shall absolutely seal, without regard to its speed of operation. The best valves for this purpose are of the plunger type and are relatively slow in operation. Under these circumstances it is desirable that the

other shall be quick-acting. The tightness 55 of seal of this quick-acting valve is not of the same importance as its speed because of the presence of the plunger valve.

Though the valve herein has other valuable uses it is intended primarily for use as 60 the quick-operating blow-off valve of such a pair. It affords a tight seal and has a desirably short face-to-face length in the direction of steam travel.

The valve casing is split transversely into 65 two parts for convenience of access, the parts being shown at 6 and 7. These are bolted together, as at 8, and are packed at 9.

They may be secured to the adjoining piping in any desired way, and I have illustrated a flange 10 at one side and a threaded opening 11 at the opposite side. In the form shown in Figure 1 the steam preferably 70 passes through in the direction of the arrow.

The body of the valve is provided with a 75 main opening through oppositely-facing fixed seats 13 and 14, against one of which the valve disk 15 is adapted to be pressed in the closed position of the valve by reason of the pressure of the steam. The seat against 80 which the disk is pressed is determined by the direction of steam passage through the valve. With that indicated by the arrow it would be seat 14.

However, it is my intention to seal the 85 disk against a seat on each side, effectively sealing on both sides. This not only adds to the tightness of the seal generally, but in large measure relieves the space 12 of pressure. For this purpose, I provide a 90 movable seat in the form of a sealing bushing or sleeve 16. Its interior diameter is that of the aperture 17 in the disk, which also has a recessed face 18.

The bushing is pressed against the disk by 95 a spring 19. It engages the opposite side 20 of the disk from the side 21 which seals against the seat 14. The bushing is provided with annular packing, as at 22, and rests against a stop 24. This may be adjustable and removable and threaded into the valve, where it is desired to make the spring tension adjustable or to provide for removal of the parts from the flanged side in Figure 1; or it may rest against a fixed 100 stop 24', as in Figure 3, if these parts are not to be removable and adjustable in this way.

It will be evident that the sleeve or bushing 16 will grind against the disk 15, in operation, and by the wear will maintain tight surface contact.

5 The disk 15 may be made separate from its arm 25, where this is desired and I have shown this construction in Figures 1 and 2, where the arm 25 is inserted within an opening 26 and is held in longitudinal position 10 with respect to the disk by a cotter pin 27.

The arm 25 is apertured at 28 for the non-circular end 29 of a shaft 30 by which the arm is swung. The shaft 30 is flanged at 31 to rest against packing 32 within a recess 33 15 and the flange is pressed against the packing by a spring 34 which rests against the side of the recess 12 and presses against the end 29. The shaft 30 turns within an opening 35 in the part 7 of the valve casing. It 20 is operated by an arm 36.

In Figure 3 the seats 13 and 13' on opposite sides of the space 12 are alike and each surrounds a movable seat 16 (and 16') of the character seen at the left in this figure, 25 giving a combination of a fixed and movable seat on the side toward which the steam is flowing and a movable seat effective upon the opposite side.

In the form shown in Figures 4 and 5, 30 the valve is also made in two parts, 6' and 7', but both of these parts are flanged for attachment to the adjoining pipe sections. However, the valve disk 15' here is given a straight line sliding movement, guided by 35 the contour 37 of its space 12'. It is moved by a thread 38 upon a shaft 39, turned by the ordinary valve wheel 40.

Whether the form be that of a swing gate valve, as in Figures 1-3, or a slide gate valve, as in Figures 4 and 5, the construction 40 offers the same opportunities for differences in many details, besides those noted,

in applying the principles of my invention and my second illustration is for the purpose, largely, of indicating that my invention is advantageous with both forms. 45

Having thus described my invention, what I claim as new and desire to secure by Letters Patent is:

1. In a blow-off valve, a valve body having a steam passage through it, oppositely spring-pressed movable valve seats surrounding the passage, circumferential packing for the seats, a valve movable across the passage and means for moving the valve. 50

2. In a blow-off valve, a valve body having a steam passage through it, oppositely spring-pressed, movable valve seats surrounding the passage, circumferential packing for the seats, a valve movable across the 60 passage, a fixed valve seat surrounding one of the movable seats and means for moving the valve.

3. In a blow-off valve, a valve body having a steam passage through it, oppositely 65 spring-pressed, movable valve seats surrounding the passage, circumferential packing for the seats, a valve movable across the passage, a fixed valve seat surrounding each of the movable seats and means for moving 70 the valve.

4. In a blow-off valve, a valve body having an opening through it for steam passage and oppositely-facing fixed valve seats surrounding the opening, a valve movable 75 between the two seats, axially movable valve seats coaxial with the fixed seats and on opposite sides of the valve, circumferential packing about the movable seats and spring means for holding one of said movable seats 80 against the valve face at the same time that the valve is pressed by the steam against the fixed valve seat upon the same side.

DAVID ROBERT YARNALL.
